ELECTRIC ELEVATOR SYSTEM

William F. Eames, Edgewood, and William R. Harding, Wilkinsburg, Pa., assignors to Westinghouse Electric Elevator Company, Chicago, Ill., a corporation of Illinois

Application August 24, 1934, Serial No. 741,270

24 Claims. (Cl. 177—336)

The present invention relates to systems of control for electric elevators and more particularly, to such systems in which a number of cars operating as a bank are controlled from push buttons located at the floor landings of the building and in the respective cars.

Earlier systems of control comprise an arrangement in which any car of a bank of cars may be stopped in response to operation of either a single up button or a single down button located in the corridor and common to all of the cars. In these systems, commonly, operation of any hall button registers a call which is maintained on the system and is not appropriated to any particular car until the arrival of a car within a short distance of the corresponding floor.

In the absence of means to predetermine which car of the system will respond to a call, it has been found impracticable to light the hall lantern at the corresponding floor until the arrival of a car at or about the slow-down point for the corresponding floor. For this reason, there is frequently a considerable period after an intending passenger has registered a call before he is given an indication as to which car of the bank will stop for him. Moreover, the lighting of the floor lantern occurs only a relatively short time before the arrival of the car at the corresponding floor landing, and it has been found that an appreciable amount of time is lost by the passenger in moving to and boarding the corresponding car.

The copending application of W. F. Eames, Serial No. 700,257, filed November 29, 1933, and assigned to the Westinghouse Electric Elevator Company, discloses a system of this general type, but in which a call, upon being registered by an intending passenger, is immediately appropriated to the nearest car travelling in the corresponding direction, regardless of the distance between such car and the corresponding floor. The appropriation to a particular car results in the immediate lighting of the floor lantern for that car at the corresponding floor, thereby immediately informing the intending passenger which car of the bank will stop for him, and enabling him to proceed to a position in front of the corresponding hatchway door.

Under certain conditions of traffic and in certain classes of buildings, it has been found desirable to enable the operator of such nearest car to determine whether his car will respond to such registered calls, and thereby overcome the possibility of more calls being appropriated to

a particular car than that car can handle expeditiously.

The present invention comprises a system similar, in many respects, to the system disclosed in the above-identified Eames application, but in which registration of a call on a passenger operated push button in the corridors immediately operates a signal in the car which is nearest, and travelling in the corresponding direction. Means are provided in each car to enable the operator thereof to appropriate such registered call to his car. The arrangement is such that although a number of calls may be simultaneously registered by intending passengers, with respect to which such car is the nearest car, the operator thereof may appropriate such calls to his car one at a time. The appropriation to a car of a call results in immediate lighting of the floor lantern for that car at the corresponding floor.

With this arrangement, the operators of the respective cars are enabled to determine at any time how many additional passengers their cars are able to accommodate, and to limit the number of calls appropriated to their cars to such number.

It is an object of the present invention accordingly to provide an elevator control system in which operation of a passenger's call button, common to all the cars, causes an immediate signal in one of the cars travelling in the corresponding direction.

It is a further object of the present invention to provide such a system in which such signal is received by the car nearest to the corresponding floor travelling in the corresponding direction, to the exclusion of the other cars.

It is a further object of the present invention to provide such a system in which each operator is provided with means to enable him to immediately appropriate such registered call to his car.

It is a further object of the present invention to provide such a system in which the means in the cars for appropriating calls thereto are common to all the floors.

It is a further object of the present invention to provide such a system in which such registered calls may be appropriated to the cars one at a time, although a number of such calls may exist simultaneously.

It is a further object of the present invention to provide such a system in which the appropriation to a particular car of a registered call results in the immediate illumination of the floor lantern for that car at the corresponding floor.

It is a further object of the present invention to provide such a system in which failure by the operator of a nearest car to respond to such a registered call leaves such registered call for a 5 succeeding car.

Other objects of the present invention will become evident from the following detailed description taken in conjunction with the accompanying drawings, in which

10 Figure 1 is a diagrammatic view showing the relationship of certain mechanical and electrical elements of an elevator system as used in the practice of the present invention.

Fig. 2 is a diagrammatic view of part of the 15 floor selector shown in Fig. 1.

Figs. 3, 4, 5, 6 and 7 taken together illustrate diagrammatically a complete control system for two cars, embodying the present invention. In these figures the circuits have been classified 20 into eight groups and the circuits included in the respective groups indicated by brackets which appear along the right-hand margin of each figure. Throughout the description, mention of a coil or contact member is in most cases followed 25 by a reference to the group in which it appears, to assist in locating it in the drawings. The locations of the respective coils and contact members are also given in a tabulation at the beginning of the detailed description of operation.

30 Except where specified the relays and switches illustrated in the drawings are conventional, each comprising a coil disposed to actuate a movable armature. The movements of the armatures open or close various contact members. In the drawings any coils and the contact members operated thereby bear the same reference characters, with the exception that the contact members have an additional identifying letter. For example, the contacts operated by coil 80U—1 are designated 35 80Ua—1, 80Ub—1, 80Uc—1, etc.

The operation of the system as a whole, and the apparatus illustrated in the respective figures 40 may be described generally as follows.

Each intermediate floor landing is provided 45 with one up push button and one down push button, common to all of the cars of the bank, for operation by intending passengers to register calls for service.

The up and down push buttons for four intermediate floors, the third, fourth, fifth and sixth, 50 are shown in Fig. 3 (Group I) and are identified by the legends C3U, C4U, C5U, C6U and C3D, C4D, C5D and C6D, respectively. A single push button is provided at each terminal landing. 55 Since the terminal push button circuits are in all respects similar to the intermediate floor push button circuits, they have been omitted from the drawings.

Calls registered by operation of the respective 60 push buttons are maintained temporarily on a set of call-registering relays, common to all of the cars. These relays are shown in Fig. 3, Group I. The up relays for the third, fourth, fifth and sixth floors are designated A3U, A4U, A5U and A6U, respectively, and the down relays as A3D, 65 A4D, A5D and A6D, respectively. Each call registering relay comprises an actuating coil, energized in response to the corresponding push button, and a magnetically opposed resetting coil, 70 energized when the corresponding call is appropriated to one of the cars, as later described.

Operation of any call-registering relay results 75 in immediate operation of a call indicating or operator's signal in the nearest approaching car.

By the term "nearest approaching car" we mean

that car whose position, direction of operation and distance from the floor of the operated call registering relay will permit it to be stopped when it arrives at that floor. In other words it means the nearest car for the desired direction which is still capable of being stopped at the floor at which a stop call is registered at the time the call is registered. The operator's signal for cars 1 and 2, shown in Fig. 1 and in Fig. 7, Group VII are identified as F—1 and F—2, respectively.

The selection of the nearest car is accomplished by means of a group of zoning relays shown in Fig. 5, Group III. Each floor is provided with one up zoning relay and one down zoning relay, 15 all of which are common to all of the cars. The up zoning relays for the third, fourth, fifth and sixth floors are identified as S3U, S4U, S5U and S6U, respectively, and the corresponding down zoning relays are identified as S3D, S4D, S5D and 20 S6D, respectively.

Each car of the bank is provided with an operator's push button, to enable the operators to respond to calls indicated by the respective operator's signals. These are shown in Fig. 7. 25 Group VIII, the operator's push button for car 1 being identified as AB—1 and that for car 2 as AB—2. The operator's push buttons may be of any hand operated type, but are preferably semi-portable and connected to the control panels 30 in the respective cars by means of flexible cords, as shown in Fig. 1.

Operation of the operator's push button transfers the registered call from a call-registering relay to a corresponding call-storing relay. Each 35 floor is provided with an up and a down call-storing relay individual to the respective cars. The call-storing relays are shown in Fig. 4, Group II, the up call-storing relays for car 1 for the third, fourth, fifth and sixth floors being designated B3U—1, B4U—1, B5U—1 and B6U—1. Those for the down direction are designated B3D—1, B4D—1, B5D—1 and B6D—1. The corresponding call-storing relays for car 2 are similarly designated but have a suffix 2 instead of 1. 45 The call-storing relays are similar in structure to the call-registering relays, each comprising an actuating coil energized through a circuit controlled by the zoning relays, the corresponding call-registering relays and the operator's push button, and a resetting coil energized when the 50 associated car stops at the corresponding floor.

As soon as a call has been transferred from a call-registering relay to a call-storing relay, the call-registering relay is reset, and maintained so until the car associated with the call-storing relay stops at, and leaves, the corresponding floor. The call-registering relay cancelling circuits are shown in Fig. 6, Group V, and include an up 55 cancelling relay and a down cancelling relay for each floor common to all the cars. The up relays for the third, fourth, fifth and sixth floors are designated M3U, M4U, M5U and M6U, respectively. The down relays are designated M3D, M4D, M5D and M6D. As is later described, operation of any cancelling relay completes the circuit for the resetting coil of the corresponding call-registering relay.

The arrangement of the actuating circuits for the call-storing relays is such that although a 60 number of calls may be registered simultaneously in the zone for a particular car, a single operation of the operator's push-button for that car results in the appropriation to that car of only one call. The call so appropriated is for the floor 65 70 75

nearest the car. Through this arrangement, the operator of the car may determine how many calls his car is to receive. If he discovers that his car has become fully loaded, he may fail to operate his operator's push-button in response to his operator's signal. Calls stored on the call-registering relays, to which the operator of such nearest car fails to respond, are maintained for the next following car. Any calls previously appropriated to such nearest car remain effective to stop it at the corresponding floors.

Prolonged closure of an operator's push-button results in lighting a warning signal in the corresponding car, and also results in isolating that car from the zoning system. The warning lights for cars 1 and 2 are shown in Fig. 1 and in Fig. 7, Group VIII, and are designated as W—1 and W—2, respectively. Additional warning signals 24—1 and 24—2 for cars 1 and 2, respectively, are shown in Fig. 3, Group I, for operation in the event an operator fails to respond to the operator's signals F—1 and F—2, respectively. The latter signals are preferably located at the dispatcher's station and will serve to warn the dispatcher that the corresponding car is being isolated from the zoning system.

As soon as a call is appropriated to one of the cars, by operation of the corresponding operator's button, a floor lantern corresponding to that car and located at the floor corresponding to the registered call is immediately lighted. Each car is provided with an up and a down floor lantern for each floor. The up floor lanterns associated with car 1, for the third, fourth, fifth and sixth floors are shown in Fig. 6, Group VI, the up floor lanterns being designated respectively as L3U—1, L4U—1, L5U—1, and L6U—1 and the down floor lanterns as L3D—1, L4D—1, L5D—1, and L6D—1. The up and down floor lanterns for car 2 are similarly designated but have a suffix 2. The floor lanterns, upon being lighted in the manner above indicated, remain lighted until the car stops at and leaves the corresponding floor.

Each car of the bank is provided with a set of buttons including one button for each floor, located within the respective cars for the purpose of registering stop calls for floors at which passengers desire to leave the car. These stopping buttons are preferably collected in a panel, together with the operator's signal, warning light and operator's push-button, as shown in Fig. 1.

The circuits for the car buttons for cars 1 and 2 are shown in Fig. 5, Group IV, the buttons for the third, fourth, fifth and sixth floors for car 1 being designated as PR3—1, PR4—1, PR5—1 and PR6—1, respectively. The car buttons for car 2 are similarly designated but have a suffix 2. The car buttons are manually closable but are provided with retaining coils, adapted to maintain the associated button in the closed position after having been closed manually. The retaining coils, which appear immediately below the corresponding buttons, are normally energized and are arranged to be momentarily deenergized each time the associated car is reversed.

Each car is provided with a stopping relay arranged to respond to either the car buttons or the call-storing relays for the corresponding car as the car approaches a floor at which a call has been registered. The stopping relays are shown in Fig. 5, Group IV, and are designated 38—1 and 38—2, for cars 1 and 2, respectively. Operation of the stopping relay for either car prepares circuits which cause the associated car to slow down and stop.

As shown in Fig. 1, the elevator car is attached to a cable c which passes over a sheave 3 to a counterweight 4 to provide a direct traction drive. Sheave 3 is mounted on the shaft of a hoisting motor 5, together with the drum of a spring-applied electro-magnetically-released brake 6. The circuits directly concerned with the control of the motor 5 form no part of the present invention, but have been illustrated as of the "variable voltage" or Ward-Leonard type, and are shown in Fig. 7, Group VIII.

Referring to Group VIII, the armature 5 is directly connected to the armature of a generator G. Generator G is provided with a separately excited field winding Gf, which may be selectively excited to determine the direction and speed of elevator motor 5, in a well known manner. Suitable speed regulating apparatus for the system is illustrated as comprising a series field GS on generator G. The starting and acceleration of motor 5 is controlled by an up button BU—1 and a down button BD—1, preferably mounted in the car station panel in the manner indicated in Fig. 1. The details of the motor control system are described later.

The slow-down and stopping of motor 5 is preferably controlled by means of switches of the type shown in Patent No. 1,902,602, granted March 21, 1933 to Williams et al. and assigned to the Westinghouse Electric & Manufacturing Company. As there illustrated, such switches comprise an energizable winding, an iron core and a plurality of contact fingers. The contact fingers are so disposed in the magnetic circuit of the coil that energization of the coil is ineffective to cause movement of the contact fingers.

The magnetic circuit is so arranged, however, that movement of a magnetizable plate into the region of the switch actuates a contact finger. Preferably, each of the contact fingers has associated therewith a magnetizable plate which, when moved into the region of the switch, actuates the corresponding contact finger and does not actuate the other fingers.

The magnetic circuit of the switch is further arranged in such a way that while the presence of a magnetizable plate is required to initially actuate a contact finger, such finger when actuated, remains in the actuated position as long as the coil of the switch is energized, even though the switch is moved away from the region of the plate.

In the illustrated embodiment of the present invention, two switches of this type are employed per car. Those for car 1 are designated 1R—1 and 2R—1.

Switch 1R—1 is used for stopping and is provided with one up inductor plate 1U per floor, and one down inductor plate 1D per floor, as shown in Fig. 1. Plates 1U and 1D are so mounted with respect to the associated floor that switch 1R—1 is brought opposite them just before the car reaches the associated floor, when travelling in the up and down direction, respectively.

Switch 2R—1 is used as a slow-down device and is provided with one up plate 2U per floor and one down plate 2D per floor. Plates 2U and 2D are so located with respect to the floors that switch 2R—1 is brought opposite them when the car reaches the slow down position for the corresponding floor when travelling in the up and down direction, respectively.

The circuits shown in Figs. 3, 4, 5, 6 and 7, Groups I, II, III, IV, VI and VII are commutated in accordance with the position of the respective

cars with respect to the floor landings by means of floor selectors individual to the cars. The driving mechanism and arrangement of the floor selector for one car is shown generally in Fig. 1, 5 and in somewhat more detail in Fig. 2. Referring particularly to Fig. 1, the driving mechanism comprises a telemotor transmitter 7, preferably of the self-synchronizing type, which is directly connected to the shaft of elevator motor 5.

10 Telemotor transmitter 7 is electrically connected with a telemotor receiver 8 of the same type, in a well known manner, so that any rotation of the armature of transmitter 7 produces a proportional rotation, in a corresponding direction, of 15 the armature of receiver 8.

Telemotor receiver 8 serves as a driving device for floor selector 9, which comprises a vertically mounted base panel 10, upon which are secured suitable guide rails 11 for a pair of vertically 20 movable cross-head members 12 and 13. The cross-head members 12 and 13 are mechanically connected together by means of a chain 14 which passes over an idler sprocket 15, rotatably mounted on the base panel 10, and a driving sprocket 16, 25 rotatably supported by means of a casing 17 mounted upon the base panel 10. The casing 17 contains suitable gearing (not shown) for transmitting the motion of the armature of the telemotor receiver 8 to the driving sprocket 16.

30 The construction so far described is such that movements of the elevator car 1 are reproduced on a smaller proportionate scale as movements of the cross-head members 12 and 13. Although either cross-head member 12 or 13 may move 35 upward in response to upward movement of the car 1, depending upon the phase sequence of the electrical connections between telemotor transmitter 7 and telemotor receiver 8, it is assumed that the telemotor connections are such that 40 cross-head member 13 moves upward when the car moves upward and covers its entire path of travel from bottom to top while the elevator car 1 is moving from its lower terminal limit to its upper terminal limit.

45 The cross-head members 12 and 13 each support a number of conducting brushes, disposed to engage and disengage groups of conducting segments mounted on the panel 10.

The rows of segments and brushes are shown 50 in relation to their associated circuits in Figs. 3, 4, 5, 6 and 7. The positions of the several brushes with respect to the segments for various positions of the car are shown in Fig. 2.

Referring to Fig. 2, fifteen rows of segments 55 are illustrated. Each row includes one segment per floor, and each segment is designated by a reference character which identifies the floor and row with which it is associated. The segments in rows b, d, f, h, j, n and r, in the left hand 60 portion of Fig. 2, under the legend "down segments", cooperate with the brushes on cross-head 12, to commute various circuits during downward travel of the car. The segments in rows a, c, e, g, i, k, m and p, in the right hand portion 65 of Fig. 2, beneath the legend "up segments", cooperate with brushes on cross-head 13 to commute various circuits during upward travel of the car. Segments 3k-1, 6k-1, 5k-1 and 6k-1 70 cooperate with two brushes on cross-head 13, one brush being effective during down travel and one brush being effective during up travel of the car.

The brushes which cooperate with the segments in rows a, c, e, g, i, k, m and p, respectively, are designated a-1, c-1, e-1, g-1, i-1,

kD-1, kU-1, m-1 and p-1. In Fig. 2, these brushes are shown in the position they occupy with respect to the segments when the car is standing at the fifth floor. The positions occupied by these brushes when the car reaches the slow down position for the fifth floor travelling upward is shown by circular elements which appear a short distance below the respective brushes. Similarly, brushes b-1, d-1, f-1, h-1, j-1, n-1 and r-1 which cooperate with the segments in rows b, d, f, h, j, n, and r, respectively are shown in their relative positions to the down segments when the car is standing at the fifth floor. The position of these brushes when the car is at the slow down position in advance of the fifth floor, travelling downwardly, is indicated by circular elements under the respective brushes. These relative positions are also indicated in a legend at the bottom of Fig. 2.

20 The brushes which cooperate with rows a and b control the dispatcher signal 24-1, previously mentioned. These brushes engage a segment just after the car passes the slow down point for the corresponding floor and pass out of engagement with the segment just before the car reaches the corresponding floor. (Group I.)

25 The brushes which cooperate with the segments in rows c and d control the resetting of the call registering relays. These brushes engage a segment just before the car reaches the slow down point for the corresponding floor and remain in engagement with the segment until the car passes a short distance beyond that floor. (Group I.)

30 The brushes which cooperate with the segments in rows e and f control the resetting of the call-storing relays. These brushes engage a segment just before the car reaches the slow down point for the corresponding floor, and remain in engagement until the car passes a short 35 distance beyond that floor. (Group II.)

35 The brushes which cooperate with the segments in rows g and h control the actuation of the call-storing relays. These brushes pass out of engagement with a segment just before the car reaches the slow down point for the corresponding floor, and are in engagement with the segment for the next floor when the car is standing at any floor. (Group II.)

40 The brushes which cooperate with the segments in rows i and j control the zoning relays, there being two brushes per row spaced a short distance apart. Both brushes of a pair are in engagement with a segment when a car reaches the slow down point for the corresponding floor. When the car moves a very short distance beyond such floor, the leading brush of the pair engages a segment for the next floor and the trailing brush passes out of engagement with the segment for the floor which the car is leaving. The brushes are so spaced that two segments are engaged simultaneously for a short distance of car travel. (Group III.)

45 The brushes which cooperate with the segments in row k control the energization of the stopping relay 38-1. As previously mentioned, the segments in this row are effective during both upward and downward travel of the car. Accordingly, an up brush kUi is provided to cooperate with the segments in row k during upward travel and a down brush kD1 is provided to cooperate with the segments in row k during downward travel. Brushes kUi and kD1 come into engagement with a segment just before the car reaches the slow down point for the corresponding floor 50 55 60 65 70 75

and pass out of engagement with the segment just after the car passes that point. (Group IV.)

The brushes which cooperate with the segments in rows *m* and *n* control the lighting of the floor lanterns. These brushes engage a segment just before the car reaches the slow down point for the corresponding floor and remain in engagement with that segment until the car has moved a short distance beyond the corresponding floor. (Group VI.)

The brushes which cooperate with the segments in rows *p* and *r* control the lighting of the operator's signals F-1 and F-2. These brushes pass out of engagement with a segment just before the car reaches the slow down point for the corresponding floor, and are in engagement with the segment for the next floor while the car is standing at such corresponding floor. (Group VII.)

20 The following tabulation gives the function of the various relays and switches and identifies the group in which any coil or contact is located.

Coil and contact locations

DETAILED DESCRIPTION OF OPERATION

Referring again to Figs. 3, 4, and 5, the operation in detail of the system is as follows. The first part of this description covers the starting of one car and the stopping thereof from its car buttons. The second part covers the stopping of any car of a bank of cars in response to hall calls.

Assuming that switch 20, at the top of Fig. 3 has been closed, thereby energizing line conductors 21 and 22, which extend throughout Figs. 3, 4 and 5, and further assuming that car 1 was travelling in the upward direction when it arrived at the fifth floor, the circuit for the coil of up-direction-determining relay 80U-1 (Fig. 7, Group VIII) is completed and remains so until the car either reaches a terminal landing or is reversed by operation of the down starting button BD-1 (Fig. 7, Group VIII).

The circuit for relay 80U-1 extends from line conductor 21 through the normally closed contact *a* of down starting button BD-1, coil 80U-1, normally closed contact members 80DK-1 of the down-direction-determining relay, and limit switch LU-1, to negative line conductor 22. Limit switch LU-1 may be of any conventional type, disposed to respond to the arrival of the car at the upper terminal.

Upon completion of this circuit relay 80U-1 is actuated to close contact members 80Ua-1, 80Ub-1, 80Uc-1, 80Ud-1, 80Ue-1, 80Uf-1, 80Ug-1, 80Uh-1, 80Ui-1 and 80Uj-1 and to open contact members 80Uk-1.

The closing of the *a*, *b*, *c*, *d*, *e*, *f* and *j* contact members of relay 80U-1 prepare circuits associated with the call-registering relays, the call storing relays, the zoning relays and the operator's signal F-1. These circuits are concerned with the response to hall calls, and are discussed in the second part of this description.

The closing of contact members 80Ug-1 prepares a circuit for the coil of relay 38-1 (Group IV), thereby conditioning the system to respond to car calls during upward travel.

The closing of contact members 80Uh-1 completes a circuit for the retaining coils associated with car buttons PR3-1, PR4-1, PR5-1 and PR6-1. This circuit is shown in Group IV and includes the retaining coils, in parallel, and contact members 80Uh-1.

The closing of contact members 80Ui-1 completes a circuit for the up fifth floor lantern L5U-1 associated with car 1, thereby advising any intending passengers at the fifth floor that car No. 1 is there and is conditioned to travel upwardly. This circuit is shown in Group VI

and includes lantern L5U—1, fifth floor selector segment 5m—1, selector brush m—1, contact members 80Ui—1, and contact members GR6b—1, which are closed at this time.

5 The opening of contact members 80Ui—1 prevents completion of a circuit for down direction determining relay 80D—1 (Group VIII).

10 OPERATOR CLOSES UP-STARTING BUTTON BU—1,
STARTING CAR UPWARDLY
10 *Switch RU—1 closes*

Closure of the up starting button BU—1 (Group VIII) for car 1 completes a circuit for up-reversing switch RU—1 to thereby cause car 1 to start upwardly. This circuit includes the normally open contact members b of starting button BU—1, coil RU—1, an interlock RDb—1 of the down reversing switch, and contact members a of stopping relay 1R—1. Upon completion of this circuit up-reversing switch RU—1 closes contact members RUa—1, RUc—1, RUd—1, RUE—1 and RUf—1, and opens contact members RUb—1, all of which are included in Group VIII.

25 *RU—1 self-holding circuit*

Closure of contact members RUa—1, which are connected directly in parallel with the contact members b of button BU—1, completes a self-holding circuit for coil RU—1, so that only a momentary closure of up button BU—1 is necessary.

Generator field Gf excited

Contact members RUd—1 and RUE—1 complete a circuit for the separately excited field winding Gf of the generator G. This circuit includes a slow-down resistor R—1 which limits the field current to a relatively low value, sufficient to cause a low operating speed of hoisting motor 5.

40 *Brake 6 releases; relay M—1 operates; car starts*

Contact members RUf—1 complete a circuit for the release coil of the electromagnetic brake 6 and for the coil M—1 of a holding relay. Upon the release of the brake and the completion of the field circuit for generator field winding Gf, motor 5 starts the car upwardly from the fifth floor at a low speed. Relay M—1 closes contact members Ma—1, and prepares a circuit for the coils of slow-down and stopping switches 2R—1 and 1R—1.

The opening of contact members RUb—1 prevents completion of a circuit for down-reversing switch RD—1.

55 *Accelerating switch GR6—1 closes*

Closure of contact members RUc—1 completes a circuit for the coil GR6—1 of an accelerating switch, which also includes the normally closed contact members of slow-down switch 2R—1. Upon completion of this circuit switch GR6—1 opens contact members GR6a—1, GR6b—1 and GR6c—1 and closes contact members GR6d—1.

65 *Fifth floor lantern L5U—1 extinguished*

Contact members GR6a—1 are associated with the resetting circuits for the call-storing relays of car 1 and their effect is described in the second part of this description. Contact members GR6b—1, in opening, extinguish the up fifth floor lantern L5U—1 (Group VI). Contact members GR6c—1 prevent energization of the coil of stopping switch 1R—1 while the car is travelling 75 at high speed.

Car at full speed

Contact members GR6d—1 are in parallel with resistor R—1 (Group VIII) and upon closure short-circuit this resistor and apply full field current to field winding Gf. To simplify the drawings, the closure of the accelerating contact members GR6—1 is shown as occurring almost simultaneously with the closure of the reversing switch contact members RUd—1 and RUE—1. In practice, the closure of the accelerating contact members will be slightly delayed. The application of full field current to generator G results in full speed operation of motor 5 and of the elevator car.

Upon completion of the above described circuits, in response to the momentary closure of up starting button BU—1, the car will continue to travel upwardly at high speed until intercepted by a call, or until a terminal is reached. To simplify the drawings, apparatus for accomplishing the stopping of the car at terminal landings has not been illustrated. Such apparatus may consist in conventional terminal slow-down switches, but preferably also includes call-registering and call-storing circuits similar in all respects to those which have been illustrated for the intermediate floors.

OPERATOR REGISTERS CAR CALL, STOPPING CAR AT 30
6TH FLOOR

Button PR6—1 closed

Assuming the operator desires to stop the car at the sixth floor, he may operate the sixth floor car button PR6—1, at any time before the car reaches the slow down point for the sixth floor. Operation of this button after the car has approached too closely to the sixth floor to permit a normal stop, is of no effect.

Stopping relay 38—1 operates

Button PR6—1, upon being manually closed, is held closed by the retaining coil shown immediately below it, as previously described. When closed, button PR6—1 prepares a circuit for the coil of stopping relay 38—1, as shown in Group IV. Just prior to the arrival of the car at the slow down point for the sixth floor, selector brush kU—1 engages segment 6k—1, and completes the circuit for the coil of relay 38—1, prepared by button PR6—1. As shown in Fig. 5, this energizing circuit for relay 38—1 remains complete until the car has passed a short distance beyond the slow down point for the sixth floor, at which time the selector brush kU—1 passes out of engagement with segment 6k—1.

Relay Q operates; slow-down switch 2R—1 energized

Upon energization of coil 38—1, contact members 38a—1 (Group VIII) are closed, and complete a circuit for the coils of slow-down switch 2R—1 and an auxiliary holding relay Q—1. Upon completion of this circuit, relay Q—1 operates and closes contact member Qa—1. These contact members are in parallel with contact members 38a—1 and complete a holding circuit for coils 2R—1 and Q—1.

Switch 2R—1 passes plate and operates; switch 70 GR6—1 deenergized

As previously mentioned, energization of the coil of slow-down switch 2R—1 has no immediate effect upon contact members a and b of this 75

switch. When the car, in its upward movement, brings slow-down switch 2R—1 adjacent the up slow down inductor plate 2U associated with the sixth floor, as shown in Fig. 1, contact members *a* thereof are actuated to the open position. The opening of these contact members interrupts the circuit for the coil of accelerating switch GR6—1. Switch GR6—1 accordingly opens contact members GR6d—1 and recloses contact members GR6a—1, GR6b—1 and GR6c—1.

Car slowed down; lantern L6U—1 lighted; switch 1R—1 energized

The opening of contact members GR6d—1, in parallel with resistor R—1, reduces the generator field current and consequently initiates the slowdown of the car. Contact members GR6c—1 complete a circuit for the coil of stopping switch 1R—1 thereby preparing it for operation. Reclosure of contact members GR6a—1 is without effect at this time. Reclosure of contact members GR6b—1 completes a circuit for the up sixth floor lantern L6U—1, since at this time brush M—1 is in engagement with the sixth floor selector segment 6m—1, as shown in Fig. 6. This circuit lights up the sixth floor lantern, informing any intending passengers at the sixth floor of the approach of the car.

30 *Switch 1R—1 passes plate and operates; switch RU—1 deenergized*

When the car approaches within a short distance of the sixth floor, stopping switch 1R—1 is brought opposite the up stopping plate 1U, as shown in Fig. 1, and contact members *a* thereof are opened. The opening of these contact members interrupts the circuit for coil RU—1, opening contact members RUa—1, RUC—1, RUD—1, RUe—1 and RUf—1 and closing contact members RUb—1.

Generator field deenergized; brake applied; car stopped; relay M—1 and Switches 2R—1 and 1R—1 deenergized

45 The opening of contact members RUa—1 and RUC—1, and the closure of contact members RUb—1, is without effect. The opening of contact members RUf—1 deenergizes the release coil of the electro-magnetic brake and deenergizes coil M—1. The opening of relay M—1 has no effect other than to prevent energization of the coils of slow down and stopping relay 2R—1 and 1R—1 when the car is at rest. The opening of contact members RUD—1 and RUe—1 interrupts the circuit for the field winding GF of generator G. This operation, together with the application of brake 6, brings the car to rest at the sixth floor.

60 *OPERATOR CLOSES DOWN STARTING BUTTON BD—1
STARTING CAR DOWNWARDLY*

As long as the car remains at the sixth floor, up-direction-determining relay 80U—1 will remain energized to condition the selector for further up travel, and the up sixth floor lantern L6U—1 will remain lighted. Further operation of the car in the up direction may be accomplished by momentarily reclosing up starting button BU—1, to thereby start and accelerate the car to high speed in the manner previously described. If, however, it is desired to reverse the car and travel downwardly from the sixth floor, down button BD—1 may be operated.

Up direction determining relay 80U—1 deenergized; car buttons released; lantern L6U—1 extinguished

Operation of down button BD—1 opens its contact members *a* and closes its contact members *b*. The opening of contact members BDa—1 deenergizes the coil of up-direction-determining relay 80U—1. Accordingly, this relay resumes the deenergized position, opening contact members 80Ua—1, 80Ub—1, 80Uc—1, 80Ud—1, 80Ue—1, 80Uf—1, 80Ug—1, 80Uh—1, 80Ui—1, and 80Uj—1 and reclosing contact members 80Uk—1. As previously mentioned, the *a, b, c, d, e, f, and j* contact members of relay 80U—1 are concerned with the response to hall calls and their effect is described in connection with the response to hall calls. The opening of contact members 80Uh—1 interrupts the circuit for the retaining coils associated with the car buttons (Group IV), thereby restoring any operated car buttons to the illustrated open position. The opening of contact members 80Ui—1 interrupts the circuit for the up sixth floor lantern L6U—1, thereby extinguishing this lantern (Group VI). The opening of contact members 80Ug—1 disconnects the up floor selector brush kU—1 as shown in Group IV.

Down direction determining relay 80D—1 operates

30 Reclosure of contact members 80Uj—1 completes a circuit for the coil of down-direction-determining relay 80D—1. This circuit is shown in Group VIII and includes the now closed contact members *a* of button BU—1, coil 80D—1, contact members 80Uk—1, and a limit switch LD—1, arranged to be opened when the car reaches the lower terminal.

On completion of this circuit, relay 80D—1 closes contact members 80Da—1, 80Db—1, 80Dc—1, 80Dd—1, 80De—1, 80Df—1, 80Dg—1, 80Dh—1, 80Di—1, and 80Dj—1 and opens contact members 80Dk—1. The *a, b, c, d, e, f and j* contact members of relay 80D—1 are associated with the circuits of the call-registering relays, the call-storing relays, the zoning relays and the operator signal F—1, and their effect is described later in connection with the response to hall calls.

Car button retaining coils energized

The closing of contact members 80Dh—1 completes a circuit for the retaining coils associated with the car buttons, as shown in Group IV.

55 *Lantern L6D—1 lighted*

60 The closing of contact members 80Di—1 completes a circuit for down sixth floor lantern L6D—1, thereby advising any intending passengers at the sixth floor that car No. 1 is conditioned to travel downwardly. This circuit is shown in Group VI and includes lantern L6D—1, sixth floor selector segment 6n—1, selector brush *n*—1, contact members 80Di—1 and contact members GR6b—1 which are closed at this time since the car is at rest.

65 The opening of contact members 80Dk—1 prevents completion of a circuit for the coil of relay 80U—1. (Group VIII.)

70 *Down reversing switch RD—1 operates, causing car to travel downwardly at full speed*

75 Closure of the *b* contact members of button BD—1 completes a circuit for the coil of down reversing switch RD—1, which also includes in-

terlock contact members RD_b-1 and contact members b of stopping relay $IR-1$.

Upon completion of this circuit, down reversing switch $RD-1$ closes its contact members RD_a-1 , RD_c-1 , RD_d-1 , RD_e-1 , and RD_f-1 , and opens its contact members RD_b-1 .

Contact members RD_a-1 are connected in parallel with the b contact members of button $BD-1$ and closure thereof completes a self-holding circuit for down reversing switch $RD-1$.

The opening of contact members RD_b-1 prevents completion of a circuit for the coil of up reversing switch $RU-1$.

Closure of contact members RD_d-1 and RD_e-1 completes a circuit for the field winding GF of generator G , which also includes the slow-down resistor $R-1$. This circuit for field winding GF is the reverse of the circuit described in connection with up travel, and results in a supply to motor 5 of voltage tending to cause downward travel at low speed.

Closure of contact members RD_f-1 energizes the release coil of the electromagnetic brake 6 and coil $M-1$. Upon release of the brake and the application of low voltage to motor 5 , the car is started downwardly at slow speed. The energization of coil $M-1$, as previously described, prepares a circuit for the coils of slow-down and stopping relays $2R-1$ and $IR-1$.

Closure of contact members RD_c-1 completes a circuit for the coil of accelerating switch GR_6-1 which circuit includes the contact members b of slow-down relay $2R-1$.

Upon completion of this circuit, accelerating switch GR_6-1 opens its contact members GR_6a-1 , GR_6b-1 , GR_6c-1 and closes its contact members GR_6d-1 . Closure of contact members GR_6d-1 accelerates the car to full speed, as previously described. The opening of contact members GR_6a-1 is concerned with the operation of the call-storing relays (Group II) and is described later.

Lantern L_6D-1 extinguished

The opening of contact members GR_6b-1 interrupts the circuit for the down sixth floor lantern L_6D-1 , thereby extinguishing it (Group VI).

The opening of the contact members GR_6c-1 prevents completion of a circuit for the coil of stopping relay $IR-1$ while the car is travelling at high speed, as previously described (Group VIII).

Upon completion of the above-described circuits, the car will continue to travel downwardly until intercepted by a call or until a terminal is reached, as described in connection with up travel. While travelling downwardly, the car may be stopped, in the natural order of the floors, at any floor for which a car button is operated, providing such car button is operated before the arrival of the car at the slow-down point for the corresponding floor. This may be illustrated by assuming that car buttons PR_5-1 and PR_3-1 for the fifth and third floors, respectively, are operated.

OPERATOR CLOSES CAR BUTTONS PR_5-1 AND PR_3-1 , CAUSING STOPS AT 5TH AND 3RD FLOORS

Upon being manually closed, buttons PR_5-1 and PR_3-1 are retained in closed position by their retaining coils, shown immediately below the corresponding buttons in Group IV. Closure of these buttons prepares circuits for the coil of stopping relay $38-1$.

As shown in Fig. 2, just before the car reaches the slow-down point for the fifth floor, brush $kD-1$ engages fifth floor selector segment $5k-1$, thereby completing a circuit for the coil of stopping relay $38-1$ which also includes the now closed contact members $80Df-1$. As mentioned in connection with up direction operation and as shown in Fig. 2, this circuit remains complete until the car has passed a short distance beyond the slow-down point for the fifth floor.

As described in connection with up direction travel, stopping relay $38-1$ closes its contact members $38a-1$, thereby completing a circuit for the coils of slow-down relay $2R-1$ and auxiliary holding relay $Q-1$ (Group VIII). Relay $Q-1$, in turn, closes contact members $Qa-1$ to complete a holding circuit for coils $Q-1$ and $2R-1$.

When the car in its downward travel brings slow-down relay $2R-1$ opposite magnetic plate $2D$, contact members b thereof are actuated to the open position, thereby deenergizing the coil of accelerating switch GR_6-1 which opens its contact members GR_6d-1 , and recloses its contact members GR_6a-1 , GR_6b-1 and GR_6c-1 .

Lantern L_5D-1 lighted

Closure of contact members GR_6c-1 is without effect. The closure of contact members GR_6b-1 completes a circuit for the fifth floor lantern L_5D-1 since at this time, selector brush $n-1$ is in engagement with the fifth floor selector segment $5n-1$, and since contact members $80Df-1$ are closed (Group VI). Accordingly, the fifth floor down lantern is lighted to inform any intending passengers at the fifth floor of the approach of the car.

The reclosure of contact members GR_6c-1 completes a circuit for the coil of stopping relay $IR-1$ as previously described (Group VIII).

The opening of contact members GR_6D-1 re-includes resistor $R-1$ in the circuit of field winding GF , thereby initiating the slow-down of the car, as previously described (Group VIII).

When the car reaches a point a short distance above the fifth floor landing, stopping relay $IR-1$ is brought opposite magnetic plate $1D$ and contact members b thereof are actuated to the open position, thereby deenergizing the coil of down reversing switch $RD-1$, which opens its contact members RD_a-1 , RD_c-1 , RD_d-1 , RD_e-1 , RD_f-1 and recloses its contact members RD_b-1 (Group VIII).

Car stopped at 5th floor

The opening of contact members RD_a-1 and RD_c-1 and closure of contact members RD_b-1 is without effect. The opening of contact members RD_f-1 applies electromagnetic brake 6 and releases holding relay $M-1$ as previously described. The opening of contact members RD_d-1 and RD_e-1 deenergizes field winding GF , and, together with the application of brake 6 , brings the car to rest at the fifth floor.

As long as the car remains at the fifth floor, the down fifth floor lantern L_5D-1 will remain lighted, to inform intending passengers that the car is conditioned to travel downwardly.

Car restarted downwardly; lantern L_5D-1 extinguished

The car may be again started downwardly by reoperation of down button $BD-1$, the starting and acceleration being as previously described. As the car leaves the fifth floor, lantern L_5D-1 is extinguished by the opening of contact mem-

bers GR6b-1 (Group VI). Since no call has been assumed to have been registered for the fourth floor, the engagement of fourth floor selector segment 4k-1 by brush kD-1 is without effect. As the car approaches the slow-down point of the third floor, however, brush kD-1 engages 4th floor selector segment 4k-1, thereby again energizing stopping relay 38-1 (Group IV).

10 *Car stopped at 3rd floor; lantern L3D-1 lighted*

The stopping at the third floor in response to the energization of relay 38-1 is in all respects similar to the stopping operation described for 15 the fifth floor, third floor down lantern L3D-1 being lighted when slow-down is initiated and remaining lighted as long as the car remains at the third floor.

20 *Successive stops in response to car buttons*

It is believed obvious from the above description of the response to car calls during downward travel that the car may be stopped in its upward travel at any number of floors at which car buttons are operated, regardless of the order of operation, as long as such car buttons are operated before the slow-down point for the corresponding floor is reached.

30 RESPONSE OF SYSTEM TO HALL CALLS

Operation of zoning relays

As previously mentioned, the zoning relays shown in Group III are common to all the cars in the bank and have the effect of dividing the hatchways into zones in such a way that all the hall calls registered between the position of any one car and the next car in advance travelling in the corresponding direction, or between such one car and the corresponding terminal, are received by the call receiving mechanism of such one car, to the exclusion of the other cars. These zoning relays also prevent response by the call receiving mechanism for any one car to hall calls registered for floors which that car has passed. 45 The zoning relays for the respective floors and directions are operated as the cars pass the respective floors in the following manner.

Relay S3D operates

50 Assuming that car 1 is still standing at the third floor, conditioned to travel downwardly, as in the previous description, a circuit is completed for third floor down zoning relay S3D, since contact members 80De-1 and 80Df-1 are closed, and since trailing brush j-1 is in engagement with third floor selector segment 3j-1, as is evident from Fig. 2. Contact members Pa-1 are provided to isolate car 1 from the zoning system and are operated only in the event of a prolonged closure of the operator's button PB-1 (Group VIII). Through this circuit, down third floor zoning relay S3D remains energized as long as the car remains at the third floor, conditioned 65 to travel downwardly.

Car reversed

If the car is reversed at any floor, either 70 manually by operation of the opposite direction starting button, or automatically at terminals through the limit switches, as previously mentioned, the zoning relay associated with the previous direction of travel is deenergized and the corresponding zoning relay for the opposite direction of travel is energized.

Relay 80D-1 deenergized

For example, assuming that car 1 is reversed manually at the third floor by operation of up button BU-1, the circuit for down-direction-determining relay 80D-1 is interrupted. Relay 80D-1 accordingly opens contact members 80Da-1 through 80Dj-1 and recloses contact members 80Dk-1. The opening of contact members 80De-1 interrupts the circuit for the coil of third floor down zoning relay S3D, which thereupon falls to the deenergized position (Group III).

Relays 80U-1 and S3U operate

The reclosure of contact members 80Dk-1 completes a circuit for the coil of up direction determining relay 80U-1 (Group VIII). As a consequence, contact members 80Uf-1 close, completing a circuit for the third floor up zoning relay S3U, since with the car at the third floor trailing brush i-1 is in engagement with the up third floor selector segment 3i-1 (Group III). This circuit remains complete as long as the car remains at the third floor in condition to travel 25 upwardly.

Car leaves 3rd floor; relay S4U operates

Just after the car leaves the third floor travelling upwardly, as shown in Fig. 2, leading brush 30 i-1 engages fourth floor selector segment 4i-1 thereby completing a circuit for fourth floor up zoning relay S4U.

Relay S3U deenergized

Just after completion of this circuit, trailing brush i-1 passes out of engagement with third floor selector segment 3i-1, thereby deenergizing third floor up zoning relay S3U.

Car passes 4th floor; relay S5U operates; relay 40 S4U deenergized

Similarly, just after the car leaves the fourth floor travelling upwardly, fifth floor up zoning relay S5U is energized by the engagement of fifth floor selector segment 5i-1 by leading brush i-1, and fourth floor up zoning relay S4U is deenergized by the disengagement of segment 4i-1 by trailing brush i-1. From this description it will be seen that the arrangement is such that the up zoning relay for any floor is energized just after the car leaves the preceding floor, travelling upwardly, and remains energized until just after the car leaves that floor, travelling upwardly, unless reversal is made at such floor, in which event, the up zoning relay is deenergized at the time the reversal is initiated by the deenergization of up-direction-determining relay 80U-1.

Operation of down zoning relays

It is believed to be obvious also that during 60 downward travel of the car the down zoning relay for any floor is energized just after the car leaves the preceding floor and remains energized until just after the car leaves that floor, travelling downwardly, unless reversal is made at such floor, in which event the corresponding down zoning relay is deenergized at the time reversal is initiated by deenergizing relay 80D-1.

Zoning relays responsive to each car in system 70

As also shown in Group III, the zoning relays respond to the movements of car 2 in the same manner as described in connection with car 1, since the segments 3i-1, 4i-1, 3j-1 and 4j-1 75

are connected directly in parallel with the corresponding segments associated with car 2. Similarly, corresponding segments for additional cars would also be connected in parallel with segments 5 3i-1, 4i-1, 3j-1, 4j-1, etc. With this arrangement at any given time one zone relay is operated by each car of the bank. For example, assuming cars 1 and 2 are both conditioned to travel upwardly, and are at the fifth and third floors, respectively, as shown in Group III, fifth floor up zoning relay S5U is operated by car 1 and the third floor up zoning relay S3U is operated by car 2. If car 1 is conditioned to travel upwardly and car 2 is conditioned to travel downwardly, up 10 zoning relay S5U is operated by car 1 and down zoning relay S3D is operated by car 2. The positions and directions of travel of any other cars in the bank would similarly determine the operation of others of the zoning relays.

20 *Zoning relay contacts*

Each zoning relay is provided with *a*, *b*, *c* and *d* contacts, identified as S6Ua, S6Ub, S3Da, S3Db, etc. The *a* contacts of the zoning relays are 25 shown in Group I, and are associated with the circuits for the resetting coils of the call-registering relays A3U, A4D, etc.

Contacts S4Ua, S5Ua, etc., of the up zoning relays form interconnections between segments 30 3c-1, 4c-1, etc., associated with car 1, as well as between the corresponding floor selector segments associated with car 2. The corresponding segments of other cars of the bank would also be connected in parallel with the segments 3c-1, 35 4c-1, etc.

Zoning relay "a" contacts; call registering relay resetting

The interconnections formed by the contacts 40 S4Ua, S5Ua, etc., permit completion of the resetting circuits for any up call-registering relays associated with floors between the position of any car conditioned to travel upwardly and the next highest car conditioned to travel upwardly, or the 45 upper terminal, and prevent completion of the resetting circuit for the up call-registering relay for any floor below the position of such car. For example, assuming car 1 is standing at the fifth floor and car 2 is standing at the third floor and 50 that both cars are conditioned to travel upwardly, zoning relay contacts S5Ua and S3Ua will be opened, as previously described. Brush *c*-1 will be in engagement with segment 5c-1 and the corresponding brush of car 2 will be in engagement with the third floor segment for car 2. Accordingly, subject to operation of the cancelling 55 relays M5U, M4U, etc., later described, a circuit can be completed for the resetting coil of up call registering relays A5U or A6U, or any other higher floors (not shown) through the segment 5c-1 and brush *c*-1 and the zone relay contacts S6Ua, etc., for floors above the position of the car. Contact S5Ua of the fifth floor up zoning relay S5U, being open, prevents completion through 60 segment 5c-1 and brush *c*-1 of a circuit for the resetting coil of any up call-registering relay corresponding to a floor below the fifth floor. Contact S5Ua also prevents completion through the corresponding brush and segment of car 2, of a 65 circuit for the resetting coils of up call-registering relays A5U, A6U and those associated with higher floors.

Action of other cars

70 Similarly, circuits for the resetting coils of third

and fourth floor up call-registering relays A3U and A4U can be completed through the corresponding brush and segments associated with car 2. Contact S3Ua being open, prevents completion through the corresponding brush and segment of car 2 of a circuit for the resetting coil of any up call-registering relay for a floor below the third floor. This contact member also prevents completion of a circuit, through the corresponding brush and segment of any other car which may be positioned below the third floor, for the resetting coils of up call registering relays A3U and A4U.

75 Contact members S3Da, S4Da, etc., of the down zoning relays form corresponding interconnections between the floor selector segments of all of the cars which are associated with the circuits of the resetting coils of the down call-registering relays A3D, A4D, etc., and function to permit re-

20 setting by any car conditioned to travel downwardly of down call-registering relays between the position of such car and the next car, or the lower terminal, and to prevent resetting by such one car of any down call registering relay for 25 floors above the position of such one car. As described in connection with the up zoning relays, the contacts S3Da, S4Da, etc., of the down zoning relays also prevent resetting of down call-registering relays by any car except the car which is 30 nearest the corresponding floor.

Zoning relay "b" contacts; call-storing relays, car 1

The *b* contacts of each of the zoning relays 35 are shown in Group II, and are associated with the call-storing relays for car 1. The *b* contacts of the up zoning relays form connections between the segments 3g-1, 4g-1, 5g-1, 6g-1, which control the energization of the call storing relays 40 B3U-1, B4U-1, etc., and the *b* contacts of the down zoning relays are similarly associated with segments 3h-1, 4h-1, etc.

45 Through these interconnections, when car 1 is standing at any floor conditioned to travel upwardly, a circuit for the call-storing relay associated with any floor between the position of the car and the next highest car conditioned to travel upwardly, or the upper terminal can be completed through brush *g*-1 and the segments 50 3g-1, 4g-1, etc., engaged by it, and completion of the circuit for the call-storing relay associated with any floor below the position of the car is prevented. Also with car 1 standing at any floor conditioned to travel downwardly, a circuit can be completed through brush *h*-1 and one of the segments 3h-1, 4h-1, etc., for the down call-storing relay associated with any floor between the position of the car, and the next lowest car conditioned to travel downwardly, or the lower 55 terminal, and completion of the circuit for the down-call-storing relay associated with any floor above the position of the car is prevented.

Zoning relay "c" contacts; call-storing relays, car 2

The *c* contacts of the up and down zoning relays are also shown in Group II and control the 60 circuits of the call-storing relays B4U-2, B3U-2, etc., associated with car 2, in the manner described in connection with the *b* contacts of these relays. Similarly, the call-storing relay circuits for all other cars of the bank would have contacts 65 of the zoning relays associated therewith in the 70 75

manner illustrated for the *b* and *c* contacts of the zoning relays.

Zoning relay "d" contacts; operator's signals F-1 and F-2

The *d* contacts of the zoning relays are shown in Group VII. The *d* contacts of the up zoning relays form interconnections between the segments *3p-1*, *4p-1*, *5p-1*, etc., which control the operator's signal *F-1*, and the time relay *T-1*, as well as between the corresponding segments associated with car 2. Through these interconnections, when car 1 is standing at any floor conditioned to travel upwardly, the operator's signal *F-1* can be illuminated in response to an operated up call-registering relay for any floor between the position of the car and the floor at which the next highest upwardly moving car is positioned, or the upper terminal, and cannot be illuminated in response to operation of a call-registering relay for the floor below the position of the car. Similarly, when car 2 or any other car of the bank is standing at any floor conditioned to travel upwardly, these interconnections permit operation of the operator's signals *F-2*, etc., in response to operation of any up call-registering relay for floors between the position of such car and the next highest car conditioned to travel upwardly, or the upper terminal, and prevents operation of the operator's signals *F-2*, etc., in response to up call-registering relays for floors below the position of such car.

The *d* contacts associated with the down zoning relays *S3D*, *S4D*, etc., form interconnections between the segments *3r-1*, *4r-1*, etc., associated with car 1, as well as between the corresponding segments associated with car 2 and all other cars in the bank. These contacts of the down zoning relays function, during the downward travel of the cars, corresponding to the *d* contacts of the up zoning relays and permit operation of the operator's signals *F-1*, *F-2*, etc., in response to the down call registering relays associated with any floor between the position of car 1 or car 2 and the next downwardly moving car, or the lower terminal, and prevent operation of signals *F-1* and *F-2*, etc., in response to down call-registering relays above the positions of the respective cars.

Assuming throughout the following examples, that car 1 is the leading car, that is, the car nearest any floor at which it is assumed a call is registered, the response of the system to hall calls is as follows.

As previously mentioned, if car 1 is standing at the fourth floor and conditioned to travel upwardly, up-direction-determining relay *89U-1* and up fourth zoning relay *S4U* are energized and the up fourth floor lantern *L4U-1* is lighted.

Button C6U registers 6th floor up call; call registering relay A6U operates

If an intending passenger at the sixth floor wishes to travel upwardly and operates button *C6U*, a circuit is thereby completed for the actuating coil of up call-registering relay *A6U*, as shown in Group I. Upon completion of this circuit up call-registering relay *A6U* closes its contact members *a*, *b*, *c*, *d*, *e* and *f*.

Self holding circuit for relay A6U

Contact members *A6Ua* are connected directly in parallel with the contact members of push button *C6U* and complete a self-holding circuit for the coil of up call-registering relay *A6U*.

Contact members *A6Ub* prepare a circuit as shown in Group II for the coil of up call-storing relay *B6U-1*, associated with car 1. This circuit also includes the now closed contact members *M6Ub* of the up sixth floor cancelling relays, contact members *S5Ub* of the up fifth floor zoning relay, contact members *A5Ud* of the fifth floor up call-registering relay, segment *5g-1*, brush *g-1* (now in engagement therewith as shown in Fig. 2), contact members *80Uc-1*, and the now open contacts *Ta-1* of the time relay and *PBb-1* of the operator's push button.

Action for car 2

Contacts *A6Uc* associated with up sixth floor call-storing relay *B6U-2* for car 2 also close, but since car 1 is assumed to have been the nearest car to the sixth floor, the now open contacts *S4Uc* of the up fourth floor zoning relay prevent completion of a circuit for up sixth floor call-storing relay *B6U-2* through the corresponding brush and segment for car 2.

The opening of contact members *A6Ud* and *A6Ue*, also shown in Group II and associated with cars 1 and 2, respectively, is without effect at this time.

Operator's signal F-1 lighted; relay T-1 operates

Closure of contact members *A6Uf* of up call-registering relay *A6U* completes a circuit for the operator's signal *F-1* and the time relay *T-1* associated with car 1, as shown in Group VII. This circuit extends through contact members *A6Uf*, contacts *S5Ud*, fifth floor segment *5p-1*, brush *p-1* (now in engagement therewith as shown in Fig. 2), contact *80Uj-1*, signal *F-1* and coil *T-1* in parallel, and through the now closed contact members *PBc-1* to the other side of the line.

Upon completion of this circuit, time relay *T-1* operates, closing its contacts *Ta-1* in the circuit of brush *g-1*, Group II, and opening its contacts *Tb-1* in the circuit of warning signal *W-1* and by-pass relay *P-1* shown in Group VIII.

The consequent lighting of signal *F-1* in car 1 informs the operator thereof that at some floor between the position of his car and the upper terminal or between the position of his car and the next highest car a call has been registered by a passenger desiring to travel upwardly.

Operator closes button AB-1; relay PB-1 operates

At any time after the lighting of signal lamp *F-1*, the operator of car 1 may appropriate the call to his car by closing button *AB-1*. Closure of this button completes a circuit for the coil of relay *PB-1*, as shown in Group VIII. In response to completion of this circuit, relay *PB-1* opens contacts *PBa-1*, starts an opening movement of contact members *PBc-1*, closes contact members *PBb-1* and starts a closing movement of contact members *PBd-1*.

Contact members *PBa-1* are included in the circuits of floor selector brushes *c-1* and *d-1* as shown in Group I, and prevent the energization of a call-registering relay resetting coil through these brushes as long as the operator holds button *AB-1* in the closed position.

Call-storing relay B6U-1 operates

Closure of contact members *PBb-1* completes a circuit for the actuating coil of call-storing re-

lay B6U-1. This circuit, shown in Group II, and previously prepared by the closure of call-registering relay contact members A6Ub and time relay contact members Ta-1, extends from line 5 conductor 21 through contact members A6Ub, coil B6U-1, now closed contact members M6Ub, S5Ub, A5Ud, segment 5g-1, brush g-1 (now in engagement therewith since the car is standing at the fourth floor), contact members 86Uc-1, 10 Ta-1 and PBb-1 to line conductor 22.

Signal F-1 extinguished; relay T-1 deenergized

Contact members PBc-1 upon opening interrupt a circuit for signal F-1 and time relay 15 T-1, as shown in Group VII. The opening, as well as the closure, of these contact members is slightly delayed, preferably by means of an air or oil dashpot (not shown). The delay in opening is provided to insure closure of contact members 20 PBb-1 in Group II prior to the reopening of contact members Ta-1, connected in series therewith. The delay in closure is provided to ensure proper resetting sequence, as later described.

25 Closure of contact members PBd-1 is without effect, because contact members Tb-1, connected in series therewith, as shown in Group VIII, are provided with means, preferably an air or oil dashpot, to delay the closing movement thereof. 30 Accordingly, although coil T-1 is deenergized, as mentioned in the preceding paragraph, contact members Tb-1 are still open. The delay in closure is preferably several seconds. The circuit including contact members Tb-1 and 35 PBd-1 is used to operate warning signal W-1 and relay P-1 in the event the operator holds button AB-1 closed too long.

Self-holding circuit for relay B6U-1

40 Upon completion of the circuit for call-storing relay B6U-1, contact members B6Ua-1, B6Ub-1, B6Uc-1, B6Ud-1 and B6Ue-1 are closed. Contact members B6Ua-1 are connected directly in parallel with contact members A6Ub, and 45 in conjunction with contact members B6Ub-1, complete a self-holding circuit for coil B6U-1, as shown in Group II.

Contact members B6Uc-1 prepare a circuit for stopping relay 38-1, as shown in Group IV.

50 *Cancelling relay M6U operates*

Contact members B6Ud-1 complete a circuit for the coil M6U of the up sixth floor cancelling relay M6U, as shown in Group V. It will be observed that contact members B6Ud-1 are shown connected in parallel with corresponding contacts associated with car 2. If other cars are included in the bank, additional corresponding contacts associated therewith would also be connected in parallel with contact members B6Ud-1. The same is true of the circuits for the other up cancelling relays M5U, etc., and the down cancelling relays M8D, etc.

55 *Lantern L6U-1 lighted*

Closure of contact members B6Ue-1 completes a circuit for up sixth floor lantern L6U-1, which is lighted to inform the intending passenger at the sixth floor that his registered call 70 has been responded to and that car 1 will stop for him. It will be observed that this circuit does not include a floor selector segment or brush and is consequently independent of the distance between car 1 and the sixth floor.

75 Upon completion of the circuit for coil M6U,

as traced above, contact members M6Ua close and contact members M6Ub and M6Uc open.

Contact members M6Ua prepare a circuit for the resetting coil of call-registering relay A6U, which is shown in Group I, and includes contact 5 members A6Ua, coil A6U, contact members M6Ua, contact members S6Ua and S5Ua of the sixth and fifth floor up zoning relays respectively, segment 4c-1, brush c-1, contact members 86Ub-1, and the now open contact members 10 PBa-1.

The opening of contact members M6Ub is without effect since as shown in Group II, and previously mentioned, the circuit for call-storing relay coil B6U-1 is maintained through contact 15 members B6Ub-1.

Action when two cars are standing at same floor

The opening of contact members M6Uc prevents completion of an energizing circuit for coil 20 B6U-2 of the up sixth floor call-storing relay associated with car 2, as shown in Group II. As a consequence, even though both cars 1 and 2 were standing at the same floor, and the operator of car 2 should close the operator's button 25 PB-2, a call would not be registered on car 2. It will be observed that should two cars be standing at the same floor, conditioned to travel in the same direction, registration of a call in their zone and for that direction operates both signals 30 F-1 and F-2. The b and c contacts of the cancelling relays 6Mu, etc., are provided so that, in such event the call is appropriated to the car in which the operator's button AB-1 or AB-2 35 is operated first, and response of a call-storing relay for the other car is prevented.

If other cars are included in the same bank with cars 1 and 2, additional contact members on the call-cancelling relays would be similarly associated with the call-storing relay circuits of 40 other cars.

Button AB-1 released; relay PB-1 deenergized

If the operator releases button AB-1 after having momentarily held it in the closed position, the circuit for relay PB-1 is interrupted, and contact members PBa-1, PBb-1, PBc-1 and PBd-1 resume the illustrated positions. The effect of a prolonged closure of button AB-1 is described later.

Relay A6U reset

Reclosure of contact members PBa-1 completes the circuit for the resetting coil of call-registering relay A6U, shown in Group I and 55 previously traced. Upon completion of this circuit, the resetting coil impresses a magnetomotive force upon the relay armature in opposition to the magnetomotive force of the actuating coil and relay A6U resumes its non-actuated position, 60 opening contact members A6Ua, A6Ub, A6Uc, A6Uf, and reclosing contact members A6Ud and A6Ue.

The opening of contact members A6Ua, Group I, deenergizes both the actuating and resetting coils of call-registering relay A6U, which action is without effect, since this relay has already resumed its non-actuated position.

The opening of contact members A6Ub is 70 without effect because of the previously traced holding circuit for call-storing relay B6U-1, shown in Group II.

The opening of contact members A6Uc is without effect because of the previous opening of 75

contact members M6Uc and S4Uc in the circuit of coil B6U-2 in Group II.

Reclosure of contact members A6Ud and A6Ue associated with cars 1 and 2, respectively, and 5 shown in Group II, is without effect at this time.

The opening of contact members A6Uf prevents recompletion of the circuit for signal F-1 and time relay T-1, in response to the slightly delayed reclosure of contact members PBc-1, 10 shown in Group VII.

The opening of contact members PBB-1 interrupts the initial energizing circuit for coil B6U-1, shown in Group II, but is without effect because of the holding circuit provided 15 through contact members B6Ub-1.

The opening of contact members PBD-1 is without effect since contact members Tb-1 are still open, it having been assumed that the release of button AB-1 occurred prior to the 20 timing out of contact members Tb-1.

Action of button AB-1 summarized

To summarize briefly, the closure of button AB-1, in response to the illumination of signal 25 F-1, results in the energization of a call-storing relay associated with car 1 corresponding to the push-button operated by the intending passenger, prepares a circuit to cancel or reset the 30 corresponding call-registering relay, and opens interlocks which prevent operation of the corresponding call-storing relay associated with car 2.

The reopening of button AB-1 completes the transfer of the up sixth floor call from the call- 35 registering relay AGU to call-storing relay B6U-1, by cancelling call-registering relay A6U-1.

Effect of cars passing one another

40 As previously described, the up call registered at the sixth floor causes operation of the operator's signal F-1 in car 1 because at the time button C6U was operated, car 1 was the nearest car to the sixth floor conditioned to travel upwardly. The up sixth floor call, however, having been transferred to the up sixth floor call-storing relay B6U-1, associated with car 1, remains registered on car 1 regardless of relative 45 positions in the hatchways subsequently assumed by cars 1 and 2, since as shown in Group II, the maintaining circuit for call-storing relay B6U-1, is independent of the zoning relays.

Button BU-1 closed; car starts upwardly; relay 50 38-1 operates; car stops at 6th floor

55 Assuming that the operator of car 1 operates up button BU-1 (Group VIII), the car is started upwardly and accelerated to full speed, as previously described. When the car reaches a point a 60 short distance in advance of the slow-down point for the 6th floor, brush kU-1 engages segment 6k-1 as shown in Group IV, thereby completing an energizing circuit for stopping relay 38-1. The consequent deceleration and stopping of the 65 car at the 6th floor is as previously described.

Relay B6U-1 reset

In this case, however, in addition to the operations occurring in the course of the slow-down 70 operation previously described, the closure of contact members GR6a-1, which occurs at the time slow-down is initiated, completes a circuit for the resetting coil of call-storing relay B6U-1. This circuit is shown in Group II and includes 75 contact members B6Ua-1, the lower or resetting

coil of relay B6U-1, segment 6e-1, brush e-1, contact members 80Ud-1 and contact members GR6a-1.

Upon completion of this circuit, the opposed magnetomotive forces of the actuating and resetting coils of relay B6U-1 cause this relay to resume its non-actuated position, opening contact members B6Ua-1, B6Ub-1, B6Uc-1, B6Ud-1 and B6Ue-1. 5

The opening of contact members B6Ua-1 and B6Ub-1 in Group II is without effect since relay B6U-1 has already assumed the non-actuated position.

The opening of contact members B6Uc-1 in Group IV is without effect since stopping relay 15 38-1 has already performed its function of initiating slow-down.

Relay M6U deenergized

The opening of contact members B6Ud-1 de- 20 energizes the coil of cancelling relay M6U, which thereupon opens contact members M6Ua (Group I), and recloses contact members M6Ub and M6Uc (Group II). This operation is without effect at this time. 25

The opening of contact members B6Ue-1 is without effect since the circuit for the up 6th floor lantern L6U-1 is maintained through segment 6m-1, brush m-1, contact members 30 80Uh-1 and GR6b-1. Through this circuit lantern L6U-1 remains lighted as long as car 1 remains at the sixth floor, conditioned to travel upwardly.

False calls prevented

It will be observed that from the time the up 35 6th floor call registered by closing button C6U, was appropriated to car 1, until car 1 slowed down for the sixth floor stop, cancelling relay M6U (Group V) remains energized. As a consequence, even though button C6U is again operated by the same or another intending passenger, call-registering relay A6U is not again energized to register a false call. This is because a reclosure of button C6U in Group I would simultaneously energize not only the actuating coil of relay A6U, but also the resetting coil thereof. 40

Should such a reoperation of button C6U occur between the time car 1 started to slow down for the sixth floor and the time it left the sixth floor upwardly, or was conditioned to leave the 6th floor downwardly, relay A6U would be energized, but would almost instantaneously be reset again. This operation is as follows. 45

Reclosure of button C6U completes a circuit for actuating coil A6U in Group I as before, causing closure of contact members A6Ua, A6Ub, A6Uc and A6Uf, and causing the opening of contact members A6Ud and A6Ue. 50

Closure of contact members A6Ua again completes a holding circuit in Group I. Closure of contact members A6Ub completes a circuit for the resetting coil of call-storing relay B6U-1 (Group II), since with the car standing at the 6th floor, brush e-1 is in engagement with segment 6e-1. 60 The resetting and actuating coils of the call-storing relays, though opposed magnetically, have substantially the same number of ampere turns, so that energization of either coil operates the relay, and simultaneous energization of both coils deenergizes the relay. Accordingly, call-storing relay B6U-1 is again operated to close its contact members B6Ua-1, B6Ub-1, B6Uc-1, B6Ud-1 and B6Ue-1. 65

Closure of contact members B6Ud-1 in 70 75

Group V again energizes cancelling relay M6U which, in turn, again completes the resetting circuit for relay A6U, as shown in Group I and previously traced, thereby again restoring this 5 relay to the deenergized condition.

The closure of contact members B6Ua-1 and B6Ub-1 completes a circuit for the actuating coil of call-storing relay B6U-1, and which, being wound in opposition to the resetting coil 10 thereof, causes this relay to again resume the deenergized position.

The momentary closure of contact members B6Uc-1 in Group IV, and B6Ue-1 in Group VI, is without effect.

15 The operation just described of energizing and deenergizing the call-registering relay, the call-storing relay and the call-cancelling relay, occurs very rapidly. The momentary energization of the cancelling relay M6U can be ensured by 20 structuring the call-storing relay B6U-1 in such a way that closure of the contact members B6Ud-1 slightly precedes the closing of contact members B6Ub-1. This can, of course, be accomplished by dashpots or other expedients well known in 25 the art, and forms no part of the present invention.

It will be observed that the momentary energization of call-registering relay A6U in response to the above-described false call, tends to complete a circuit for the operator's signal F-2 and time relay T-2, associated with car 2, and shown in Group VII, which extends from line conductor 21 through contacts A6Uf, S5Ud, S4Ud, the fourth floor segment and brush for car No. 2, contact 25 members 88Uj-a and through signal lamp F-2, coil T-2, and contact members PBe-2 to the other side of the line. Completion of this circuit may be avoided either by slightly delaying the closure of the f contact members of the call- 40 registering relays, or its effect may be disregarded since the lamp is extinguished again almost immediately.

Action in response to plurality of hall calls

45 Car 1 having been assumed, at the beginning of the preceding example to be standing at the fourth floor conditioned to travel upwardly, and to have been the highest car of the bank of cars, it is believed apparent that operation of any 50 up hall button for a floor above the position of car 1 will result in immediate operation of the operator's signal F-1, and that a momentary closure in response thereto of button AB-1 will result in a transfer of the call from a correspond- 55 ing call-registering relay to a corresponding call-storing relay associated with car 1, cancellation of the corresponding call-registering relay, and immediate illumination of the corresponding floor lantern for car 1. It is believed to be ap- 60 parent that car 1 may be caused to stop successively at any number of floors for which the call-storing relays have been operated, regard- 65 less of the order of registration, so long as the transfer from a call-registering to a call-storing relay occurs before the car reaches the slow- down point for the corresponding floor, and that once a call has been transferred from a call- 70 registering relay to a call-storing relay, effective reoperation of the call-registering relay is pre- vented until such car has stopped at and moved away from the corresponding floor.

Response to hall call at next floor

It will be observed that hall calls registered 75 for a floor in advance of the floor at which the car

is standing complete a circuit for the corresponding operator's signal and the corresponding call-storing relays which are independent of the zoning relays. For example, with car 1 at the 5 fourth floor, and conditioned to travel upwardly, brush p-1 is in engagement with segment 5p-1 for the fifth floor, as shown in Group VII. Operation of the fifth floor up button energizes relay A5U which, in turn, completes a circuit for signal F-1 which extends through contact members A5Uf, segment 5p-1, brush p-1, contact members 10 88Uj-1 and through signal F-1 and relay T-1 and contact members PBe-1 to the other side of the line, and a second circuit through contact members A5Ub, actuating coil B5U-1, contact members M5Ub, to the segments 5g-1. In other respects, the 15 response of a car to a call for the next floor is similar to the response to calls for more remote floors, it having been assumed for simplicity that 20 the speed of the elevator cars is such as to permit normal acceleration and deceleration to and from full speed in the distance between adjacent floors.

Hall calls at floors which car has passed

As previously mentioned, the operator's signals for the cars respond to only those calls which are in advance of the respective cars and which correspond as to direction of travel. Assuming again that car 1 is at the fourth floor, conditioned to 25 travel upwardly, registration of a third floor up call, while effective to energize relay A3U, is ineffective to operate signal F-1, since contact members S4Ud of the fourth floor up zoning relay disconnect contact members A3Uf from segment 30 5p-1, with which brush p-1 is in engagement. Closure of contact members A3Uf, however, does 35 operate the operator's signal F-2 for car 2, assuming car 2 is positioned below the third floor and conditioned to travel upwardly.

Directional response to hall calls

As previously mentioned, contacts 88Uj-1 and 45 88Dj-1 of the direction-determining relays for car 1 prevent operation of operator's signal F-1 in response to up call registering relays except when the car is conditioned to travel upwardly and in response to down call registering relays except when the car is conditioned to travel downwardly. The corresponding direction-determining relays associated with car 2 perform the same 50 function in connection with operator's signal F-2 and the control systems of any other cars in the bank would be similarly arranged.

Hall calls transferred one at a time

As previously mentioned, although a number of 55 hall calls, corresponding in the direction of travel of the car, may be registered at the same time, such calls are transferred to that car one at a time, each operation of the operator's button being effective to transfer the call which is nearest the car. For example, assuming that car 1 is standing at the third floor conditioned to travel upwardly, and that car 2 is at some position below 60 the third floor, or is conditioned to travel downwardly, and that up calls are registered on the fourth, fifth and sixth floor hall buttons C4U, C5U, and C6U, call registering relays A4U, A5U and A6U respond, closing their respective a, b, c, 65 d and f contacts and opening their respective e contacts.

The a contacts of these call-registering relays 70 complete self-holding circuits as previously described. The b contacts of these relays close in 75

the circuits of the corresponding call-storing relays for car 1 and the *c* contacts close in the corresponding call-storing relay circuits for car 2. The *f* contacts complete three circuits in parallel 5 for signal lamp F-1 and time relay T-1 of car 1, as shown in Group VII. The *d* and *e* contacts of these relays open in the circuits of the call-storing relays for cars 1 and 2, respectively, as shown in Group II.

10 *Button AB-1 closed; relay PB-1 operates*

Closure of button AB-1 (Group VIII) energizes relay PB-1, as previously described, and contact members PBb-1 complete a circuit for 15 call-storing relay B4U-1, since brush *g*-1 is in engagement with segment 4g-1 (Group II). Contact members A4Ud being in the open position, prevent completion at this time of a circuit for either call-storing relay B5U-1 or B6U-1.

20 *Relays B4U-1 and M4U operate*

Relay B4U-1 operates, completing a maintaining circuit through contact members B4Ua-1 and B4Ub-1, preparing a circuit for stopping 25 relay 38-1 (Group IV), lighting lantern L4U-1 through contact members B4Ue-1 (Group VI), and energizing cancelling relay M4U through contact members B4Ud-1 (Group V).

30 *Button AB-1 released; relay A4U reset*

Relay M4U prepares a resetting circuit for the coil of relay A4U, which is completed upon reclosure of contact members PBa-1 in response to the release of the operator's button AB-1. Upon 35 completion of this circuit the *a*, *b*, *c*, *d*, *e* and *f* contact members of relay A4U resume the illustrated position shown in Groups I, II and VII.

30 *Button AB-1 again operated; relay B5U-1 operates*

40 If button AB-1 is again operated, a circuit is completed for call-storing relay B5U-1 and contact members A5Ud prevent completion in response to such operation of a circuit for call-45 storing relay B6U-1.

45 *Button AB-1 reclosed; relay A5U reset*

Upon release of button AB-1, a resetting circuit is completed for call registering relay A5U, 50 reclosure of contact members A5Ud of which permits operation of call-storing relay B6U-1, in response to a third operation of button AB-1.

55 *Successive operations of button AB-1*

Each time the operator's button AB-1 is operated to transfer a nearest call, the operator's signal F-1 is extinguished by the opening of contact members PBc-1. Upon release of the operator's button AB-1, however, the operator's signal F-1 is again lighted as long as calls remain 60 in the zone for car 1, and for the corresponding direction.

It will be observed that the above-described operations of transferring calls registered on the 65 call-registering relays, while dependent upon the direction in which the car is conditioned to move, are independent of whether the car is at rest at a floor or moving.

70 *Effect of failure to operate button AB-1 or AB-2*

As previously mentioned, the feature of enabling the operator of a car to transfer calls to a car one at a time is provided to accommodate 75 varying traffic conditions in the building. If at

the time an operator receives a signal by means of his lamp F-1 or F-2, he observes that his car is not in condition at that time to receive additional passengers, he may fail to operate his button AB-1 or AB-2 in response thereto.

Assuming that car 1 is at the third floor conditioned to travel upwardly, that car 2 is below the third floor or is conditioned to travel downwardly, and that a call has been registered on the up sixth floor button C6U, relay A6U re- 10 sponds, lighting operator's lamp F-1, as previously described. If button AB-1 is not closed, lamp F-1 remains lighted but the sixth floor up call is not transferred to call-storing relay B6U-1, because contact members PBb-1 remain

15 open. Car 1 may be started upwardly by operation of button BU-1, as previously described. Just after it leaves the third floor, fourth floor up zoning relay S4U will be energized and third floor up zoning relay S3U will be deenergized.

20 As it passes the fourth floor, relay S5U will be energized and relay S4U will be deenergized. As it passes the fifth floor, relays S6U and S5U will be energized and deenergized, respectively. Closure of contact members S5Ud of the up fifth 25 floor zoning relay S5U immediately permits completion of a circuit through contact members A4Uf, for the operator's signal associated with the first car below car 1 travelling upwardly, or conditioned to travel upwardly. If the operator

30 of such following car appropriates the up sixth floor call to his car, up sixth floor call-registering relay A6U is reset, and the opening of contact members A6Uf extinguishes the lamp F-1 in car 1.

If no other car is travelling upwardly or conditioned to travel upwardly at the time, or fails to respond to his operator's signal, the operator's lamp F-1 in car 1 remains lighted until car 1 reaches a point just in advance of the slow- 35 down point for the sixth floor. At this time, brush *p*-1 disengages segment 6p-1, thereby extinguishing lamp F-1. Relay A6U remains effective to operate the call receiving mechanism of the next lowest car which becomes conditioned to travel in the corresponding direction.

40 45 *Operation of dispatcher's signals 24-1 and 24-2*

In the event an operator does fail to operate his button AB-1 or AB-2 in response to a registered call, as previously described, a signal 24-1 or 50 24-2 shown in Group I and preferably located at a dispatcher's station is operated. Referring to Group I, the circuit for dispatcher's signal 24-1 may be completed through either up floor selector brush *a*-1, any one of the segments associated therewith, and contact members A5Ua, A6Ua, etc., of the corresponding call-registering relays, or through brush *b*-1, any of the segments associated therewith and contact members

55 A5Da, A6Da, etc., of the associated down call-registering relays, depending upon the direction in which the car is travelling, or conditioned to travel. As shown in Fig. 2, brushes *a*-1 and brushes *b*-1 engage the segment for a particular floor just after the car reaches the slow-down point for that floor, travelling in the corresponding direction, and pass out of engagement there- 60 with just before the car reaches the corresponding floor. With this arrangement, the dispatcher's signal 24-1 is not operated until a car has approached too closely to a floor to permit a normal stop at that floor. The circuits for the dispatcher's signal 24-2 associated with car 2 65 are similar in all respects, and those for other

cars of the bank would also be similarly arranged.

Operation of warning signals W-1 and W-2 and relays P-1 and P-2

5 As previously described, the transfer and re-setting of hall calls require only momentary operation of the buttons AB-1 and AB-2. Inadvertent prolonged closure thereof causes operation of a warning signal W-1 or W-2 in the 10 associated car, and isolates that car from the zoning system. This operation is as follows.

Closure of button AB-1 energizes relay PB-1 as shown in Group VIII. Relay PB-1 accordingly closes contact members PBb-1 and opens 15 contact members PBc-1 and PBa-1, the operation of which is as previously described, and starts a closing movement of contact members PBd-1.

Closure of contact members PBd-1 completes 20 a circuit for warning signal W-1 and by-pass relay F-1, as shown in Group VIII. Closure of contact members PBd-1 is preferably delayed by means of a dashpot or other conventional timing mechanism for a period slightly 25 shorter than the delay provided for the re-closure of contact members Tb-1. The lamp W-1 informs the operator of car 1 that he has held button AB-1 closed too long, and that his car is isolated from the system. Relay P-1 in 30 operating opens its contact members Pa-1 in Group III, thereby interrupting the zoning relay circuits for car 1. Any zoning relay previously operated by car 1 accordingly resumes the deenergized position. As long as contact members Pa-1 remain open, car 1 remains out of the zoning system, in which event the zone for the next car behind car 1 extends from such 35 following car to the next car in advance of car 1 travelling in the corresponding direction, or 40 to the corresponding terminal.

If the operator of car 1 holds his operator's button closed until he reaches the corresponding terminal, car 1 will receive no more calls until the corresponding terminal is reached. If he 45 releases his button at some intermediate point in the hatchway, relay PB-1 is deenergized, contact members PBd-1 deenergize relay P-1 and the consequent reclosure of contact members Pa-1 re-includes car 1 in the zoning system, 50 by causing completion in Group III of a circuit for the zoning relay corresponding to the position and direction of travel of car 1 as previously described.

If the prolonged closure of button AB-1 just 55 described was initiated in response to a call registered on one of the call-registering relays, relay T-1 would have been operated at the same time operator's signal F-1 was operated, as 60 previously described, and contact members Tb-1 would have been opened. A reclosing movement of these contact members would have been initiated by the opening of contact members PBc-1, as 65 previously described. In this event the operation of warning signal W-1 and relay P-1 would have been delayed for the period determined by the timing of the closing movement of contact members Tb-1. In this event also, release of button AB-1 to re-include car 1 in the zoning 70 system would have resulted in the resetting of the call-registering relay, the circuit for which is as described in the previous examples.

If no call were registered in the zone for car 1, and for the corresponding direction, at the 75 time of the prolonged closure of button AB-1,

the operation of warning signal W-1 and relay P-1 would have been delayed for a period determined by the timing on contact members PBd-1, since in this event contact members Tb-1 would have not been opened. As previously mentioned, the delay in closure of contact members PBd-1 is somewhat shorter than the delay in reclosure of contact members Tb-1.

Under normal operating conditions, the operator of a car will be enabled to notice the operation of his operator's signal F-1 or F-2 and will consequently operate his button AB-1 or AB-2 only in response to such signals. If, however, signal F-1 or F-2 should fail, or if the operator should find it necessary to devote his entire attention to passengers, it is desirable that he should intermittently and momentarily close his operator's button AB-1 or AB-2. From the previous description, it will be apparent that such intermittent momentary operation will be effective to transfer any registered calls which are in the zone for his car and for the corresponding direction, to the call-storing relays for his car, even though operator's signal F-1 may have failed to operate in response to such registered calls. Because of the timing on contacts PBd-1 and on the corresponding contacts associated with car 2 and with the other cars of the bank, such intermittent momentary operations of the operator's buttons will not operate the warning signals or the relays P-1, P-2, etc.

It will be observed that the operation of relay P-1 simply prevents receipt by the corresponding car of further hall calls, and does not affect the response of that car to calls previously transferred to the call-storing relays, and does not permit re-operation of the call-registering relays corresponding to such previously transferred calls. This is because, as shown in Group II, the circuits for the call-storing relays of all the cars having once been completed, are maintained independently of the zoning relays. For this same reason, when a car is re-included in the zoning system it prevents receipt by following cars of additional hall calls for the corresponding direction and in the zone of such re-included car, but does not affect the response by such following car to any hall calls transferred to the call-storing relays of such following car during the time that the re-included car was isolated from the zoning system. Through this arrangement, when an intending passenger has been directed to a particular hatchway by the lighting of the corresponding lantern, he is not confused by subsequently being directed to another hatchway.

Although the greater part of the preceding description is given in connection with the apparatus associated with car 1, the apparatus for car 2 is identical with that for car 1, and it is believed unnecessary to repeat the description on the assumption that car 2 is the nearest to a registered call. Similarly, although up calls have been assumed throughout the greater part of the description, the up and down circuits common to both cars and individual to the respective cars are identical, so that it is believed unnecessary to repeat the description assuming down calls.

Although a specific embodiment of the present invention has been illustrated and described, it is to be understood that various modifications may be made therein, and it is desired, therefore, that no limitations shall be placed upon the present

invention other than are imposed by the prior art or defined in the appended claims.

We claim as our invention:

1. In a system for operating a plurality of elevator cars past a plurality of floors, passenger operated call registering means for each of said floors, a signal for each of said cars common to all the floors, and means comprising means responsive to operation of the call-registering means for any floor for immediately operating the signal for the nearest approaching car for said floor, and for preventing operation of the signals for the other cars.

2. In a system for operating a plurality of cars past a plurality of floors, call registering means for each of said floors common to all of said cars, a signal for each car common to all of said floors, zoning means responsive to the positions of said cars, and means controlled by said zoning means for causing an immediate operation, in response to operation of the call-registering means for any floor, of the signal for the nearest approaching car for said floor.

3. In a system for operating a plurality of cars past a plurality of floors, call-registering means for each of said floors common to all of said cars, a signal for each car common to all of said floors, zoning means responsive to the positions of said cars, and means controlled by said zoning means for causing an immediate operation, in response to operation of the call-registering means for any floor, of the signal for the nearest approaching car for said floor and for preventing operation in response to said operated call-registering means of the signals for the other cars.

4. In a system for operating a plurality of elevator cars past a plurality of floors, a relay per floor common to all of said cars, a relay per floor individual to each car, a switch in each car common to all of said floors, zoning means responsive to the positions of said cars and means responsive to the common relay for any one floor and said zoning means for rendering a switch effective to operate the relay individual to the corresponding car for said one floor.

5. In a system for operating a plurality of elevators past a plurality of floors, a relay per floor common to all of said cars, a relay per floor individual to each of said cars, a switch in each car, means responsive to each switch for actuating the relays individual to the corresponding car, zoning means responsive to the positions of said cars and means responsive to the common relays and said zoning means for determining which of said individual relays are to be operated in response to operations of said switch.

6. In a system for operating a plurality of elevator cars past a plurality of floors, a relay per floor common to all of said cars, a relay per floor individual to each car, a switch means in each car common to said floors, means responsive to said common relays for rendering said switch means effective to operate the relays individual to the respective cars, and means responsive to the relative positions of said cars with respect to the floor associated with any operated common relay for determining which of said switch means is to be rendered effective.

7. In a system for operating a plurality of elevator cars past a plurality of floors, call-registering means for each floor common to all of said cars, a relay per floor individual to each car and circuits therefor, a signal in each car, zoning means responsive to the positions of said cars, means controlled by said zoning means for rendering the call-registering means for any floor

effective to cause immediate operation of the signal in the nearest approaching car for said any floor and for preparing the circuit for the relay individual to said nearest car for the corresponding floor, and a switch in each car for completing the circuits for the relays individual to the associated car.

8. In a system for operating an elevator car, the combination of a first series of relays; a second series of relays; a switch; and means responsive to operation of said switch for rendering each of said relays of said second series operably responsive to a corresponding relay in said first series, said last named means comprising means to prevent operation of more than one of said relays of said second series in response to a single operation of said switch.

9. In a system for operating a plurality of elevator cars, the combination of a first series of relays common to said cars; a second series of relays individual to one of said cars; a switch; and means responsive to repeated operations of said switch to operate one at a time the relays of said second series corresponding to operated ones of said first series.

10. In a system for operating a plurality of elevator cars past a plurality of floors, the combination of a first series of relays, one for each of said floors common to said cars; a second series of relays, one for each of said floors individual to one of said cars; a switch; means responsive to repeated operations of said switch to operate one at a time the relays of said second series corresponding to operated relays of said first series, said last named means including means controlled in accordance with the position of said car for determining which relay of said second series is to respond to a particular operation of said switch.

11. A system for operating a plurality of elevator cars past a plurality of floors comprising call means individual to each of said floors common to said cars for registering calls for service; mechanism individual to each of said cars for responding to calls for service; zoning means responsive to the positions of said cars; switch means individual to each of said cars common to said floors; and means controlled jointly by said zoning means and said switch means for rendering the said mechanism for said cars effective to respond to calls registered on said common call means.

12. A system for operating a plurality of elevator cars past a plurality of floors comprising a control individual to each of said floors common to said cars for registering calls for service; decelerating mechanism for each of said cars; zoning means responsive to the positions of said cars for determining zones of said floors in which the respective cars shall receive calls; switch means individual to each of said cars and common to said floors; and means responsive to the switch means for any of said cars for rendering the decelerating mechanism for that car responsive to any operated floor control in the zone for said any car.

13. A system for operating a plurality of elevator cars past a plurality of floors comprising a control individual to each of said floors common to said cars; decelerating mechanism individual to each of said cars; switch means individual to each of said cars common to said floors; signal means individual to each of said cars common to said floors; zoning means responsive to the positions of said cars; means controlled by

said zoning means and responsive to any operated floor control for actuating the said signal means for one of said cars and for rendering the said switch means for that car effective to cause 5 actuation of the said decelerating mechanism for that car upon the approach of that car to the floor corresponding to said operated floor control.

14. Transfer mechanism for elevator systems 10 comprising a first relay means; a second relay means; means for operating said first relay means; a transfer device; means responsive to closure of said transfer device for rendering said second relay means responsive to said first relay 15 means and means responsive to release of said transfer device for resetting said first relay means.

15. In a system for operating a plurality of elevator cars past a plurality of floors, the combination 20 of call means individual to each of said floors common to said cars for registering calls for service, zoning means controlled by the positions of said cars, switch means individual to each of said cars common to said floors, and 25 means controlled by said zoning means to render a said switch means operable to appropriate a call registered on said common means to the associated car.

16. A system for operating a plurality of elevator cars past a plurality of floors comprising 30 a control individual to each of said floors common to said cars, decelerating mechanism for each of said cars, zoning mechanism responsive to the positions of said cars, switch means individual to each of said cars common to said floors, and 35 means controlled by said zoning mechanism for rendering a said switch means operable to cause actuation of the said decelerating mechanism for the associated car upon the approach 40 of that car to a floor corresponding to an operated floor control.

17. In an elevator system for operating a plurality of cars past a plurality of floors, a call registering means for each of said floors common 45 to all of said cars, a signal device for each car common to all of said floors, a normally ineffective switch means for each car common to said floors, zoning means responsive to the positions 50 of said cars, means controlled by said zoning means and responsive to operation of a call registering means for a floor for immediately operating the signal device in the nearest approaching car for that floor and for preparing the switch means in that car for effective operation, and 55 means responsive to operation of that switch means and to the approach of that car to within a predetermined distance of the floor of the operated call registering means for stopping the car when it arrives thereat.

60 18. In an elevator system for operating a plurality of cars past a plurality of floors, a call registering device for each of said floors common to all of said cars, a call storing device for each floor for each car, a signal device at each floor for 65 each car, a signal means in each car common to all the floors, a switch means in each of said cars common to all the floors, zoning means responsive to the positions of the cars, means controlled by the zoning means and responsive to 70 operation of a call registering device at a floor for operating the signal means in the nearest approaching car for that floor and for rendering effective the switch means in that car, means responsive to operation of the switch means in 75 the car of the operated signal means for trans-

ferring the registered call from the operated call registering device to the call storing device for the corresponding floor for that car, and means responsive to the operated call storing device for immediately operating the signal device for that car at that floor. 5

19. In an elevator system for operating a plurality of cars past a plurality of floors, a call registering device for each floor common to all the cars, a plurality of storing relays one for each floor for each car, zoning means responsive to the positions of the cars for defining a signal zone ahead of each car, a signal device in each car common to all the floors, a switch in each car common to all the floors, means responsive to the operation of the call registering devices at a plurality of floors in the signal zone of a car for operating the signal device in that car, means responsive to the operation of the switch in the car for transferring the call registered on the call registering device for the nearest floor for that car's operation to the call storing device for that floor for that car and for preventing the transfer of additional registered calls in response to that operation of the switch but responsive to the next subsequent operation of said switch for transferring the next nearest registered call from its operated call registering device to the call storing device for the corresponding floor for said car, and means responsive to operation of said operated call storing devices and to the approach of the car to the corresponding floors for stopping the car thereat. 20 25 30

20. In an elevator system for operating a plurality of cars for a plurality of floors, a call registering means for each floor common to all the cars whereby intending passengers at the floors may register stop calls for the nearest approaching cars, zoning means for providing a signal zone ahead of each car up to the next car beyond it, a stopping means for each car, and a quota means including a switch device for each car and means responsive to each operation of the switch device by an attendant for a car for accepting one registered stop call in the signal zone ahead of that car to cause the stopping means to automatically decelerate and stop the car as it arrives at the floor of the accepted call or calls whereby the attendants may control the number of stop calls their cars will make during each trip. 35 40 45 50

21. In an elevator system for operating a plurality of cars for a plurality of floors, a call registering means for each floor common to all the cars whereby intending passengers at the floors may register stop calls for the nearest approaching cars, zoning means for providing a signal zone ahead of each car up to the next car beyond it, a stopping means for each car, and a quota means including a switch device for each car, means responsive to each normal operation of the switch device by an attendant for a car for accepting one registered stop call in the signal zone ahead of that car to cause the stopping means to automatically decelerate and stop the car as it arrives at the floor of the accepted call or calls whereby the attendants may control the number of stop calls their cars will answer during each trip, a warning signal device, and means responsive to more than a normal period of operation of said switch device for operating the warning signal device to indicate that the attendant is maintaining the operation of said switch device for more than its normal period of operation. 60 65 70

22. In an elevator system for operating a plurality of cars for a plurality of floors, a call regis- 75

tering means for each floor common to all the cars whereby intending passengers at the floors may register stop calls for the nearest approaching cars, zoning means for providing a signal zone 5 ahead of each car up to the next car beyond it, a stopping means for each car, and a quota means including a switch device for each car, means responsive to each normal operation of the switch device by an attendant for a car for accepting one 10 registered stop call in the signal zone ahead of that car to cause the stopping means to automatically decelerate and stop the car as it arrives at the floor of the accepted call or calls whereby the attendants may control the number of stop calls 15 their cars will answer during each trip, and means responsive to operation of said switch device for more than its normal period of operation for disconnecting the car from the zoning means to eliminate the signal zone for that car.

20 23. In an elevator system for operating a plurality of cars serving a plurality of floors, a call registering means for each floor common to all the cars whereby intending passengers at the floors may register stop calls for the nearest 25 approaching cars, means for effecting the stopping of said cars in response to registered calls, a signal device disposed at a dispatcher's floor for each car, and means responsive to a nearest approaching car passing a floor for

which a stop call has been registered for operating the signal device at the dispatcher's floor for that car to indicate to the dispatcher that that car has not answered that registered call.

24. In a system for operating a plurality of elevator cars past a plurality of floors, a control individual to each of said floors common to said cars, signal devices individual to each of said cars and common to said floors, a switch means individual to each of said cars and common to said floors, zoning means responsive to the positions of said cars, means controlled by said zoning means and responsive to the operation of a floor control for operating the signal device in the nearest approaching car for the floor of the operated control and for preparing for effective operation the switch means of that car, means responsive to operation of said switch means and to the approach of said car to the floor of the operated control for stopping the car at that floor, a signal device for each car disposed at a dispatcher's office, and means responsive to a nearest approaching car passing the floor of an operated control without stopping thereof for operating the dispatcher's signal device for that car to indicate that it has passed a stop call without answering it.

WILLIAM F. EAMES.

WILLIAM R. HARDING.
